PRINTING CYLINDER

John R. Tomlin, Alexandria, Va., assignor, by
mesne assignments, to R. Hoe & Co., Inc., New
York, N. Y., a corporation of New York

Application March 13, 1934, Serial No. 715,315

14 Claims. (CL. 101—415.1)

This invention relates to printing cylinders, and more particularly to printing cylinders of the type having gaps, and which are constructed and arranged to operably support flexible sheet metal printing plates.

In cylinders of this type, it is desirable that as much of the peripheral surface of the cylinders as possible be utilized for impression purposes, and in certain kinds of printing cylinders, such as those employed in intaglio printing machines for photogravure or rotogravure printing, it is desirable that the entire peripheral surface of the plate cylinders be employed in the printing operation. Until recently, photogravure or rotogravure printing had been done on a printing machine employing a relatively thick copper cylinder or shell mounted on the peripheral portion of the intaglio plate cylinder on which the subject or design had been produced by the usual intaglio pits or wells. This cylinder rotated in ink which filled the pits or wells of the intaglio design, and the surplus ink was scraped from the face of the plate by the usual stationary doctor plate positioned at a desirable scraping angle relative to the periphery of the cylinder.

This method, while producing satisfactory printing, proved very expensive, especially where a variety of subjects had to be printed. After the required number of prints of a subject had been made, the peripheral surface of the cylinder was ground down, polished, and a fresh subject then produced thereon; or, alternatively, a large number of expensive intaglio printing cylinders had to be kept in store.

More recently it has been proposed to mount a flexible printing plate, having a design in intaglio thereon, around the periphery of the cylinder, the terminals of the plate being suitably secured to the cylinder. These flexible plates are capable of ready removal and replacement, and this arrangement has considerably reduced the cost of photogravure or rotogravure printing. However, the existing devices and means for securing the flexible printing plate to the periphery of the cylinder are either very expensive to manufacture, lack sufficient rigidity, or leave gaps between the plate terminals which interfere with the operation of the doctor blade. As hereinbefore stated, it is desirable that certain types of printing cylinders, which operably support flexible sheet metal printing plates, be constructed and arranged to utilize as much as possible of the periphery of each printing cylinder for impression purposes. This is particularly so in offset printing presses employing flexible sheet zinc

planographic plates. In this type of press, by employing the entire peripheral portion of the plate cylinder for impression production, a larger sheet for a given cylinder size can be printed, and continuous designs can also be printed on webs in offset web printing or web perfecting presses.

An object of the present invention is to provide a printing cylinder having operable components for securely binding a flexible printing plate around the periphery of the cylinder, the cylinder and the components being constructed and arranged so that the entire circumference of the cylinder is made available for impression production.

Another object of this invention is to provide a plate cylinder for receiving a flexible printing plate around the periphery thereof, the cylinder having components operable to securely lock the flexible printing plate on the cylinder, and coacting to fill the peripheral portion of the cylinder gap to thereby complete the cylinder periphery.

A further object of the invention is the provision of a printing cylinder incorporating means for securing one terminal of a flexible printing plate to the cylinder, and coacting components, to one of which the plate terminal is secured, operable to securely bind the flexible plate around the cylinder, and to interfit to close the cylinder gap and to securely lock the plate in printing position.

An additional object of the invention is to provide a printing cylinder having a flexible sheet metal printing plate thereon, and coacting members for locking the plate in printing position and for filling the peripheral portion of the cylinder gap, and manually operable means for actuating the coacting plate locking members and for rigidly supporting them against movement under impression stresses when in their plate securing or gap filling position.

It is also an object of my present invention to provide a printing cylinder of generally improved construction and arrangement, whereby the device will be simple, durable and inexpensive in construction, as well as convenient, practical, serviceable and efficient in its use.

With the foregoing and other objects in view, which will appear as the description proceeds, the invention resides in the combination and arrangement of parts, and in the details of construction hereinafter described and claimed, it being understood that various changes in form, proportions and minor details of construction

may be resorted to without departing from the spirit or sacrificing any advantages of the invention.

For a complete disclosure of the invention, a detail description of a printing cylinder embodying the invention in a preferred form will now be given in connection with the accompanying drawings forming a part of this specification, wherein:

10 Figure 1 is a fragmental elevation, parts appearing in section, of one end of a printing cylinder, its components shown in plate securing position;

15 Figure 2 is a fragmental vertical section depicting one end of the improved printing cylinder, parts appearing in elevation, the view looking in the direction of arrow 2 of Figure 1;

20 Figure 3 is a fragmental plan view of one end of the printing cylinder, parts appearing in section, the view being taken in the direction of arrow 3 of Figure 4; and

25 Figure 4 is a fragmental elevation, similar to Figure 2, but depicting the plate clamping components in plate releasing position.

25 Referring to the drawings, in which similar reference characters designate corresponding parts, 10 indicates a printing cylinder of the type employed in photogravure or rotogravure and offset printing, the cylinder being provided with a gap 11. An undercut recess 14 is formed in the gap 11 at one side thereof for the reception of a clamping bar 15, which is secured to the cylinder by suitable clamping screws or members 16. One terminal 18 of a flexible sheet metal printing plate

30 19 is clamped within the recess 14 by the bar 15, and the plate is then bent around the periphery of the cylinder 10, and its opposed terminal 20 secured within a recess 21, formed in the plate clamping or securing member 22, by means of

35 a clamping bar 23, which is secured to the member 22 by suitable clamping screws or members 25. The printing plate 19 may be of the usual planographic type employed in offset presses, or it may have its design produced in intaglio there-

40 on by means of the usual pits and wells. When employed as an intaglio printing plate, the cylinder, in conformity with present practice, rotates in an ink fountain, thereby depositing the ink in the intaglio cavities, and the surplus ink is then 45 scraped from the surface of the plate by means of the usual doctor blade, not shown, but the construction and purpose of which is well understood by those skilled in the art.

45 The plate clamping or securing member 22 is movable within the gap 11 for securing and releasing the flexible plate 19, and in the preferred construction illustrated, it is pivotally secured to brackets 28 by means of suitable shafts or trunnions 29, and the brackets 28 are secured to the 50 cylinder 10 by suitable machine screws or securing devices 30. In order to positively move the plate securing member 22 about its pivotal point 29 to force or stretch the plate 19 into secure printing position, a coacting member or wedge 35 is provided and is arranged to slide within the gap 11 and a recess 36 which communicates with the gap. The opposed walls 38 and 39 of the recess 36 and gap 11 positively guide the wedge or member 35 for right line or rectilinear motion, 55 and suitable instrumentalities, to be hereinafter disclosed, are provided for imparting motion to the wedge 35. The plate clamping member 22 is provided, at a point remote from its pivotal point 29 with a hardened angularly disposed wedge 70 engaging surface 40, and an outer arcuate sur-

face 41, the arc of which is concentric with the arc of the periphery of the cylinder 10. The sliding block or wedge 35 has a hardened angularly disposed surface 43 which is arranged and positioned to engage and coact with the hardened 5 surface 40 of the member 22 to move the member 22 to closed or plate clamping position. An arcuate surface 44 is formed at the outer terminal of the wedge 35, and its arc is also concentric with the arc of the cylinder periphery. The outward sliding motion of the sliding block or wedge 35 is limited by a shoulder 45 formed in the wall 39, and a similar shoulder 46 formed in the wedge 35. In order to secure the wedge 35 against longitudinal motion in its recess 36, suitable guide 15 pins or dowels 48 are secured to the wedge 35, as indicated at 49, and these dowels are slidably received in cylindrical recesses 50 formed in the cylinder 10.

55 In order to positively move or slide the wedge 20 35, an annulus or toggle ring 55 is mounted on each end of the cylinder shaft 12, and each ring has a connecting member or link 56 pivotally secured thereto, as indicated at 57, and the opposed terminal of this link is pivotally secured to 25 the slidable wedge 35, as indicated at 58. By this arrangement, as the ring 55 is rotated on the shaft 12, it, coacting with the link 56, produces a toggle action which forcibly moves the wedge 35 outwardly, and the wedge, in turn, by 30 the engagement of its angularly disposed surface 43 with the similar surface 40 of the plate securing member 22, moves the plate securing member to plate securing position.

55 A shaft 60 extends longitudinally through the 35 cylinder and is mounted for rotation within the cylinder. At the opposed ends of this shaft there are provided suitable pinions 62, having teeth 63, which mesh with similar teeth 64 formed on the outer periphery of each toggle ring 55, and a 40 wrench engaging or actuating head 66 is formed at each end of the shaft 60.

60 A pawl 70 is pivotally secured to the cylinder 10, as indicated at 71, and this pawl is provided with teeth 72 which engage the teeth 63 of the 45 pinion 62, thereby locking the pinion 62 against rotation. The free end of the pawl 70 is yieldingly pressed toward the pinion 62 by a spring 74, which has one end secured to the cylinder, as indicated at 75, and its opposed terminal engaging the pawl 70. A manipulating handle 76 is secured to the free toothed end of the pawl 70, and this handle extends through a slot 77, formed in one of the casings 78 arranged to house the mechanism operably located at each end of the 55 cylinder 10.

65 Inasmuch as the mechanism at each end of the cylinder is provided in duplicate, only one end of the cylinder is here illustrated, but it is, of course, to be understood that both ends are similar in construction and arrangement to that illustrated, except that it is not necessary to employ more than one locking pawl 70.

70 In operation, assuming that the parts are in the position indicated in Figure 4, and it is desired to secure a flexible printing plate to the cylinder, the locking pawl 70 is moved from engagement with the teeth of the pinion 62 by manually moving the handle 76 in a direction away from the pinion 62, and a suitable wrench is placed on the squared portion 66 of the shaft 60, and the ring 55 is thereby rotated counter-clockwise. Inasmuch as the pivotal point 57 of the ring 55 moves about the center of the shaft 12, a toggle action is produced between the ring 75

and the link 56 thereby forcibly moving the wedge 35 outwardly, which, in turn, forces the plate securing member 22 about its pivot 29 to the position indicated in Fig. 1, thereby drawing the plate 19 around the cylinder 10 and immovably securing it to the periphery of the cylinder. It is to be understood, of course, that the terminals of the plate have been previously secured in the recess 14 and 20 of the cylinder 10 and the plate 10 securing member 22 by the clamping bars 15 and 23. In order to insure that the plate will be of proper dimension to accurately fit the periphery of the cylinder it is preferred that the plate first be bent around a template of predetermined dimensions and then secured, as described, to the cylinder. When the components of the cylinder are in plate securing position, as shown in Fig. 1, the pivotal joint 57 will have moved slightly beyond a radial line passing through the pivotal point 58 and the center or axial point of the shaft 12, and in this position the locking pawl 70 is moved into engagement with the teeth of the pinion 62, thereby rigidly securing the wedge 35 and plate securing member 22 against retrograde or inward motion.

When the cylinder is constructed and arranged for photogravure or rotogravure printing, it is necessary that the interfitting parts adjacent the periphery of the cylinder 10 be accurately proportioned and accurately interfitted to insure an uninterrupted peripheral surface. The components of the cylinder are in manufacture, moved to plate securing position, as indicated in Figure 1, before the periphery of the cylinder is given its final dimension, and then the cylinder is ground down to predetermined dimension so that the arcuate surfaces 41 of the plate securing member 22 and the arcuate surface 44 of the wedge 35 accurately coincided with the arc of the cylinder periphery. The wedge engaging surface 40 of the member 22 and the angular surface 43 of the wedge 35, together with the opposed sliding surfaces of the wedge 35 and the wall surface 39 of the gap 11 are accurately ground to produce precision fit, thus when the components are in plate securing position uninterrupted peripheral surface is produced, thereby insuring a continuous support for the flexible plate 19 to prevent the interfitting joints of the components affecting the printing or impression surface of the plate.

When the plate is employed in intaglio printing, the minute recess or cavity defined by the small arcs 80 of the abutting terminals 71 of the plate 19 may be filled by suitable plastic composition, which, when hardened, will present a smooth surface for operable engagement with the doctor blade, thus producing an uninterrupted peripheral plate surface so that any preferred design may be employed in either intaglio or offset printing without affecting the continuity of design, in offset work, or interfering with the operation of the doctor blade, in gravure printing.

Having thus described my invention, what I claim as new and useful in the art is:—

1. A printing cylinder having a gap, means for securing one terminal of a flexible printing plate to the cylinder, coacting movable members, means for securing the opposed terminal of the flexible printing plate to one of the coacting movable members, means operably supported by the cylinder for forcibly moving one of the movable members thereby forcibly moving the coacting movable members to plate securing position to

securely bind the flexible plate around the periphery of the cylinder, the movable members each having an arcuate surface of the same radius as the periphery of the cylinder so that said arcuate surfaces coincide with the periphery of the cylinder when the movable members are in plate securing position thereby closing the gap to complete the peripheral portion of the cylinder. 5

2. A printing cylinder having a gap, means 10 for securing one terminal of a flexible printing plate to the cylinder, a movable member pivotally supported by the cylinder, means for securing the opposed terminal of the printing plate to the movable member, a second movable member 15 slidably supported by the cylinder and operably engaging the first movable member to forcibly move the first movable member about its pivot to plate securing position, thereby securely binding the flexible plate around the periphery of 20 the cylinder, each movable member having an arcuate surface of the same radius as the periphery of the cylinder so that said arcuate surfaces coincide with the periphery of the cylinder when the movable members are in plate securing 25 position thereby closing the gap to complete the peripheral portion of the cylinder.

3. A printing cylinder having a gap, means for securing one terminal of a flexible printing plate to the cylinder, a movable member operably supported by the cylinder and having an arcuate surface of the same radius as the cylinder, means for securing the opposed terminal of the flexible printing plate to the movable member, a second movable member supported 30 by the cylinder and having an arcuate surface of the same radius as the cylinder, means operably supported by the cylinder for operating the second movable member to cause it to operably engage the first movable member to forcibly 40 move it to plate securing position to securely bind the flexible plate around the periphery of the cylinder and to close the gap so that the said arcuate surfaces complete the peripheral portion of the cylinder. 45

4. A printing cylinder having a gap, means for securing one terminal of a flexible printing plate to the cylinder, a movable member pivotally supported by the cylinder and having an arcuate surface of the same radius as the cylinder, means for securing the opposed terminal of the flexible printing plate to the movable member, a second movable member slidably supported by the cylinder and having an arcuate surface of the same radius as the cylinder, means for moving the second movable member to operably engage the first movable member to forcibly move it to plate securing position thereby securely binding the flexible printing plate around the periphery of the cylinder, the arcuate surfaces of both movable members coinciding with the periphery of the cylinder when in plate securing position to close the gap and complete the peripheral portion of the cylinder. 55 60

5. A printing cylinder having a gap, means for 65 securing one terminal of a flexible printing plate to the cylinder, coacting movable members each having an arcuate surface of the same radius as the cylinder, means for securing the opposed terminal of the flexible printing plate to one of the 70 coacting movable members, manually operable means operably supported by the cylinder for forcibly moving the coacting movable members to plate securing position thereby securely binding the flexible plate around the periphery of the cyl- 75.

inder, both movable members being constructed and arranged to move in the gap away from the periphery of the cylinder to open the gap and to move toward the cylinder periphery so that the arcuate surfaces thereof coincide with the periphery of the cylinder when in plate securing position to close the gap and complete the peripheral portion of the cylinder.

6. A printing cylinder having a gap, means for securing one terminal of a flexible printing plate to the cylinder, a movable member pivotally supported by the cylinder and having an arcuate surface of the same radius as the cylinder, means for securing the opposed terminal of the flexible printing plate to the pivotally supported movable member, a second movable member slidably supported by the cylinder and operably engaging the first movable member and having an arcuate surface of the same radius as the cylinder, 10 manually operable means operably supported in the cylinder for forcibly moving the second movable member into operable engagement with the first movable member to force the movable members to plate securing position thereby securely binding the flexible printing plate around the periphery of the cylinder, the arcuate surfaces of the movable members coinciding with the periphery of the cylinder when the movable members are in plate securing position to close the gap and complete the peripheral portion of the cylinder.

7. A printing cylinder having a gap, means for securing one terminal of a flexible printing plate to the cylinder, a movable member pivotally supported by the cylinder and positioned to operate within the gap and having an arcuate surface of the same radius as the cylinder, means for securing the opposed terminal of the printing plate to the pivoted movable member, a second movable member slidably in the cylinder and having an arcuate surface of the same radius as the cylinder, means for operating the second movable member, the second movable member being positioned to operate within the gap and constructed and arranged to operably engage the first movable member to forcibly move it to plate securing position thereby securely binding the flexible printing plate around the periphery of the cylinder, the arcuate surfaces of both movable members coinciding with the periphery of the cylinder when the movable members are in plate securing position to close the gap and complete the peripheral portion of the cylinder.

8. A printing cylinder having a gap, means for securing one terminal of a flexible printing plate to the cylinder, a pivotally supported member movable within the gap and having a wedge engaging surface and an arcuate surface of the same radius as the cylinder, means for securing the opposed terminal of the flexible printing plate to the pivotally supported member, a slidable wedge movable within the gap and having an arcuate surface of the same radius as the cylinder, means for operating the wedge, the wedge being constructed and arranged to operably engage the wedge engaging surface of the pivotally supported member to force the pivotally supported member to plate securing position thereby securely binding the flexible printing plate around the periphery of the cylinder, the arcuate surfaces of the pivotally supported member and the wedge coinciding with the periphery of the cylinder when the said member and wedge are in plate securing position to close the gap and complete the peripheral portion of the cylinder.

9. A printing cylinder having a gap, means for securing one terminal of a flexible printing plate to the cylinder, a pivotally supported member having an arcuate surface, means for securing the opposed terminal of the flexible printing plate to the pivotally supported member, a wedge having an arcuate surface, means for operating the wedge, the wedge being constructed and arranged to operably engage the pivotally supported member to force it to plate securing position thereby securely binding the flexible printing plate around the periphery of the cylinder, the pivotally supported member and the wedge being constructed and arranged so that their arcuate surfaces coincide with the periphery of the cylinder when in plate securing position to close the gap and complete the peripheral portion of the cylinder.

10. A printing cylinder having a gap, means for securing one terminal of a flexible printing plate to the cylinder, a pivotally supported member having an arcuate surface and a wedge engaging surface, means for securing the opposed terminal of the flexible printing plate to the pivotally supported member, a slidable wedge having an arcuate surface, means for operating the wedge, the wedge being constructed and arranged to operably engage the wedge engaging surface of the pivotally supported member to force the pivotally supported member to plate securing position, thereby securely binding the flexible printing plate around the periphery of the cylinder, the pivotally supported member and the wedge being constructed and arranged so that their arcuate surfaces coincide with the periphery of the cylinder when in plate securing position to close the gap and complete the peripheral portion of the cylinder.

11. A printing cylinder having a gap, means for securing one terminal of a flexible printing plate to the cylinder, coacting movable members, means for securing the opposed terminal of the flexible printing plate to one of the coacting movable members, means for forcibly moving the coacting movable members to plate securing position thereby securely binding the flexible plate around the periphery of the cylinder, stop means for limiting the movement of the coacting movable member in plate securing position, both movable members being constructed and arranged so that portions thereof coincide with the periphery of the cylinder when in plate securing position to close the gap and complete the peripheral portion of the cylinder.

12. A printing cylinder having a gap, means for securing one terminal of a flexible printing plate to the cylinder, coacting movable members having arcuate surfaces, means for securing the opposed terminal of the flexible printing plate to one of the coacting movable members, means for forcibly moving the coacting movable members to plate securing position, thereby securely binding the flexible plate around the periphery of the cylinder, stop means for limiting the plate securing movement of the coacting movable members when their arcuate surfaces coincide with the periphery of the cylinder, thereby positioning the movable members to close the gap and complete the peripheral portion of the cylinder.

13. A printing cylinder having a gap, means for securing one terminal of a flexible printing plate to the cylinder, coacting movable members having arcuate surfaces, means for securing the opposed terminal of the flexible printing plate to one of the movable members, means for forcibly moving the coacting movable members to plate securing position, thereby securely bind-

ing the flexible plate around the periphery of the cylinder, stop means for limiting the plate securing movement of the coacting movable member when their arcuate surfaces coincide with the periphery of the cylinder thereby positioning the movable members to close the gap and complete the peripheral portion of the cylinder, and means for securing the movable member in plate securing position.

10 14. A printing cylinder having a gap, means for securing one terminal of a flexible printing plate to the cylinder, a pivotally supported member having an arcuate surface and a wedge engaging surface, means for securing the opposed terminal of the flexible binding plate to the pivotally supported member, a slidable wedge hav-

ing an arcuate surface, means for forcibly moving the wedge so that it operably engages the wedge engaging surface of the pivotally supported member to force the pivotally supporting member to plate securing position thereby securely 5 binding the flexible printing plate around the periphery of the cylinder, stop means for limiting the plate securing movement of the wedge when the arcuate surfaces of the wedge and the pivotally supported member coincide with the 10 periphery of the cylinder, thereby positioning the wedge and the pivotally supported member to close the gap and their arcuate surfaces to complete the periphery of the cylinder, and means for securing the wedge in plate securing position. 15

JOHN R. TOMLIN.
